UNITED STATES PATENT OFFICE.

MAURICE ANDERSON, OF EDGEWOOD, RHODE ISLAND.

BRACELET END HOOK.

Application filed February 24, 1928. Serial No. 256,565.

This invention relates to a bracelet end hook for attaching the ends of a flexible bracelet to the bails or lugs of a wrist watch. It has for its object to provide in such a construction means for preventing the tongue which closes the opening to the hook from becoming so far sprung inwardly as to set the metal and prevent it from returning to closed position under the influence of the inherent resiliency of the stock.

A further object of this invention is to position the stop members in such a position as to prevent the bail of the wrist watch from moving beneath the tongue and interfering with an opening movement thereof.

A still further object of this invention is the securing of the tongue in position in the body of the hook by rolling portions of the body over the tongue having side walls with a serrated edge to grip a ribbon and to better bite and grip the top plate and prevent a longitudinal movement of the tongue when mounted in the body of the end hook.

With these and other objects in view, the invention consists of certain novel features of construction, as will be more fully described, and particularly pointed out in the appended claims.

In the accompanying drawings:

Figure 1 is a perspective view with parts broken away showing the hook as attached to the bail of a wrist watch.

Figure 2 is a perspective bottom view of the body part and extending shank formed into a hook.

Figure 3 is a perspective view of the tongue part.

Figure 4 is a perspective view showing the parts of the end hook assembled with a slightly modified tongue end wall.

Figure 5 is a section on line 5—5 of Figure 4.

Figure 6 is a section on line 6—6 of Figure 4.

Figure 7 is a view similar to Figure 6 showing the tongue moved to open position.

Figure 8 is a section on line 8—8 of Figure 6.

Figure 9 is a view similar to Figure 6, showing the hook attached to a ribbon.

Bracelet end hooks which have a tongue to close the opening to the hook which depends for its action upon the resiliency of the metal to move it to closed position, often become bent or set by a movement of the tongue inwardly to too great an extent and

in order to avoid this undesirable result, I have provided stop lugs carried by the tongue to limit its flexing movement and have so positioned these stop lugs adjacent 60 the end of the tongue as to prevent the bail of the wrist watch from moving beneath the tongue to interfere with its action. I have also provided a construction of two pieces of metal with the edges of the side walls of the 65 tongue serrated so that when it is secured in position by rolling of the side edges of the body over the tongue, it will better grip the top plate and prevent longitudinal movement of the tongue in the body and these serrations 70 may be used for securing the hook to a ribbon when desired and the following is a detailed description of the present embodiment of this invention illustrating one construction by which these advantageous results may be accomplished:—

With reference to the drawings 10 designates a wrist watch having a bail 11 to which the bracelet end hook 12 may be releasably attached.

The end hook consists of a body 13 having a top plate 14 and side walls 15. The top plate 14 is extended to form a shank 16 which is formed in the shape of a hook at its end as illustrated at 17.

The tongue 18 is provided with the side walls 19 which fit and rest snugly within the side walls 15 of the body and the serrated edges 20 of the side walls engage the inner surface of the top wall 14 to cause these 90 edges to bite into this top wall and prevent longitudinal movement of the tongue relative to the body when the edges 21 of the sides 15 are rolled over the tongue as illustrated in Figures 4 and 5. The portions of the side 95 walls as at 22 and of the top wall as at 23 extend inwardly to form a stop to assist in positioning the tongue in the body and holding one end of the same rigidly in position. The opposite end 24 of the tongue 100 engages the margin of the end 25 of the hook on its inner surface to close the opening 26 to the hook.

In operation the end portion 24 of the tongue is flexed inwardly to open the hook 105 and in order to limit its flexing movement, I have formed stop members 27 by folding inwardly a wing portion of the stock extending from the side edge of the tongue and I have so positioned these stop members that they 110 are adjacent the end 24 of the tongue and prevent the bail 11 from moving to a posi-

tion beneath the tongue to obstruct its operation.

The serrations 20 heretofore mentioned serve additionally with the cooperation of 5 the serrations 30 on the end wall 28 to secure a ribbon to the hook, the ribbon being placed between the top wall 14 and the tongue part 18 as the two are assembled so that the 10 rolling of the edges 21 also serves to secure the ribbon thereto.

For securing the hook to the end link of a flexible bracelet, the wall 28 is formed shorter and of a width to leave an opening 29 for insertion of the coupling member which 15 may be of the dumb-bell type having a head or end enlarged of a sufficient size to prevent withdrawing movement from the opening.

It will be apparent that I have provided an 20 end hook formed of two metal parts which may be assembled to secure a ribbon therebetween, each being such that they may be multiplied by machine operations and yet so constructed as to have means to prevent accidental injury to the tongue and thus assure 25 the tongue at all times closing the hook and preventing accidental loss of the watch and bracelet attached thereto.

The foregoing description is directed solely 30 towards the construction illustrated, but I desire it to be understood that I reserve the privilege of resorting to all the mechanical changes to which the device is susceptible, the invention being defined and limited only by the terms of the appended claims.

35 I claim:—

1. A bracelet end hook comprising a body having an extending shank formed into a hook, a tongue mounted in said body and extending into position to engage the inner 40 marginal end of said hook to close the opening thereto, and a stop member carried by said tongue spaced from the bend of the hook a distance sufficient to receive the watch bail between it and the bend of the hook, the stop 45 serving to limit the movement of the tongue towards said shank and also the movement of the hook towards the watch when in engagement with the watch bail.

50 2. A bracelet end hook comprising a body having an extending shank formed into a hook, a tongue mounted in said body and extending into position to engage the inner marginal end of said hook to close the opening thereto, a pair of stop members posi-

tioned on the side edges of the tongue and adjacent its closing edge and extending toward the shank to limit the movement of said tongue towards the shank and also to prevent a watch bail from moving beneath the tongue to obstruct its action. 55 60

3. A bracelet end hook comprising a body having an extended shank formed into a hook, said body having top and side walls, a tongue having side walls in engagement with the side walls of said body, the edges of 65 said body side walls being rolled over said tongue to secure the same in position and the edges of the side walls of the tongue being serrated to engage the top wall of the body to assist in holding the same in position. 70

4. A bracelet end hook comprising a body having a top wall and side walls, said top wall being extended to form a shank having its end shaped into a hook, a sheet metal tongue having side walls at one end fitting 75 closely within the side walls of the body and rigidly secured at said end by the rolling over of the edges of the body side walls, the free end of said tongue extending into position 80 to engage the marginal inner end of the hook to close the opening thereto, the stock of the tongue being sufficiently resilient to permit the tongue to be flexed toward said shank to open the hook, and stops formed by folding portions of the side edges of the 85 tongue toward said shank to limit the flexing movement of said tongue toward said shank. 90

5. A bracelet end hook comprising a body having an extended shank formed into a hook, said body having top and side walls, a 90 tongue having side walls serrated at their edges, a ribbon bracelet positioned between said serrated edges and the top wall and the edges of said body walls being rolled over said tongue to secure the ribbon and tongue 95 in position in said body.

6. A bracelet end hook comprising a body having an extended shank formed into a hook, said body having top and side walls, a tongue having side walls and end wall serrated at their edges, a ribbon bracelet positioned between said serrated edges and the top wall and the edges of said body walls being rolled over said tongue to secure the ribbon and tongue in position in said body. 100 105

In testimony whereof I affix my signature.

MAURICE ANDERSON.
